AUTOMATIC DUST REMOVING SYSTEM

Frank B. Allen, Lower Merion Township, Montgomery County, Pa., assignor to The Allen-Sherman-Hoff Company, Philadelphia, Pa., a corporation of Pennsylvania

Application April 16, 1943, Serial No. 483,275

6 Claims. (Cl. 302—17)

1
This invention relates generally to the art of handling finely divided solids, and more particularly to a new and improved system, method and apparatus for handling dust which is collected in powdered fuel-burning furnaces.

In modern steam generating stations which burn powdered fuel considerable quantities of finely divided incombustible solids are produced as residues of the combustion of the fuel. These solids, which are variously known as dust, fly ash, precipitator ash and the like, will be referred to hereinafter collectively as dust.

In the operation of powdered fuel-burning furnaces, part of the incombustible material in the fuel melts in the combustion chamber and is solidified and collected in hoppers from which it is periodically removed for disposal. Other fine parts of the incombustibles which are not melted are carried out of the combustion chamber with the hot gases. Some of this dust is separated from the gases in the boiler tube chambers by reversal of the direction of flow of the gases which is caused by baffles and is collected in hoppers from which it must be frequently removed and handled. Some of the dust passes thru the boiler tube chambers and is precipitated out of the gases before entering the stack by any well known electrical or mechanical precipitator and is collected in hoppers from which it must be periodically removed and handled. The dust which escapes from the combustion chamber is nuisance material for it can not be allowed to pass out thru the stack and menace the health of people and value of property and it is difficult and expensive to collect and handle. Since many tons of such dust are produced daily by a large powdered fuel-burning furnace, the seriousness of this dust nuisance is obvious.

Ever since powdered fuel fired steam boiler plants came into use efforts have been made to solve this dust nuisance by handling this dust effectively and efficiently, but so far as I know none of these efforts has been entirely satisfactory. Several conflicting factors are involved in the handling of this dust.

Since the dust is very fine and hot and since a partial vacuum and a strong draft exist within the furnace, it is impracticable to remove the dust from the furnace hoppers in the ordinary manner, that is, by opening the bottom of the hopper and letting the dust fall out by gravity. Some of the dust so discharged would be picked up and blown around in the power plant and some of it would be carried up out of the hopper and into the gases in the furnace or adjacent to the stack.

2
It has been proposed to remove such dust from the hoppers by means of currents of air flowing thru hopper valves under the influence of suction or vacuum. This proposal possesses certain difficulties. Since the dust tends to settle out of an air stream when it moves slowly or stops, it is important that all the dust be removed from a hopper without interrupting the rapid flow of air through the valve and pipe lines connected therewith. If the dust does settle out it is but slowly picked up when the air again starts to move and may, in fact, clog the pipe lines. Since the dust must be separated from the air which carries it away from the hoppers, some kind of separator is required. If the separator is not large enough to hold all the dust from one hopper it must be emptied one or more times during the removal of dust from that hopper. Since the vacuum in the separator had to be broken each time dust was discharged from it, it is obvious that the flow of air through the dust valve and piping must be interrupted with consequent settling out of dust in the pipe lines. If, to avoid such breaking of the vacuum, the separator is made large enough to receive all the dust from one hopper, the cost is high and the separator may require more space than is available for it; and even then it must be emptied before dust is removed from the next hopper and that means breaking and again building up the vacuum in the system. Thus such a system requires an operator's attention and is slow and inefficient and expensive. Furthermore, the dust discharged from the separator is not in a condition for ready handling for it is finely divided and will be picked up by any air currents which come into contact with it.

The present invention reconciles the foregoing various conflicting factors and provides a new and improved system and method, as well as new and improved apparatus, for effectively and efficiently solving this dust handling problem.

The present invention may be briefly described as follows: The dust which has been collected in a plurality of hoppers communicating with the interior of a powdered fuel furnace is removed from the hoppers, one after another in succession, and is carried through passages to a device for separating gases and fine solids, for example, a cyclone separator. This movement of the dust is accomplished by means of gas which is caused to move at adequate velocity by vacuum. The dust and gas are separated in the separator, the dust collecting in the bottom of the separator while the gas is withdrawn therefrom. The col-

lected dust is withdrawn from the separator continuously without any breakage of the vacuum existing in the separator, and stored in a hopper therebelow from which it is periodically removed, wetted and thereby fitted for subsequent handling either by a stream of water, a hopper car or the like, and delivered to such transporting means.

When the dust has been removed from one hopper the foregoing steps are automatically carried out on the dust of another hopper and are automatically repeated until all hoppers have been cleared of dust.

By means of this invention dust may be continuously and automatically withdrawn from one hopper after another by vacuum induced moving gas streams, separated from the gas and removed from the zone of influence of vacuum without breaking the condition of vacuum, and such separated dust may be wetted or otherwise conditioned for further handling.

In the drawings accompanying and forming a part of this application,

Fig. 1 is a diagrammatic view of one form of system and apparatus embodying the present invention and with which the present invention may be practiced.

Fig. 2 is a side elevational view, partly in section, of parts of the apparatus of Fig. 1;

Fig. 3 is an enlarged side elevational view, partly in section, of a dust valve of Figs. 1 and 2 with associated mechanism.

Fig. 4 is a top plan view of the separator and associated mechanism of Fig. 2;

Fig. 5 is a vertical, cross-sectional view, taken on line 5—5 of Fig. 4;

Fig. 6 is a horizontal, sectional view, taken on line 6—6 of Fig. 5;

Fig. 7 is a vertical longitudinal sectional view of the dust conditioner of Figs. 1 and 2;

Figs. 8, 9 and 10 are transverse sectional views taken on lines 8—8, 9—9 and 10—10 respectively of Fig. 7; and

Fig. 11 is a wiring diagram of an electrical system for controlling the operation of the dust valves of Figs. 1 and 2.

In Fig. 1 each of a plurality of dust hoppers 1 is provided with a dust valve 2. Groups of these valves are connected to thrusters 3 for actuation and each of the valves is connected to a pipe line 4 which leads to a separator 5. This separator communicates thru dust-withdrawal means 6 with a storage hopper 7, which in turn communicates with dust conditioning apparatus 8 from which conditioned dust may be discharged into transporting means such as car 9. Main water line 10 is connected to device 11 which serves to create and maintain a vacuum in line 12 which is connected to separator 5 and line 4 and thru branch line 13 with vacuum gage 14 on the operator's panel 15. A branch water line 16 leads from main water line 10 to water pressure gage 17 on panel 15 and communicates with branch lines 18 and 19 which lead into valves 20 and 21 which serve to break the vacuum in line 12. On panel 15 the rectangular area 22 indicates a space for signal lamps (not shown) to indicate various stages of operation of the various parts of the apparatus. Power switch 23 on panel 15 is the main power line switch, while control switch 24 on the same panel enables the operator to vary the normal sequence of operations of the electrical circuits and parts controlled thereby. The water line 10 is provided with a shut-off valve 10a and the vacuum line 75

12 is provided with another shut-off valve 12a. The device 11 may be of any form suitable for utilizing water to create vacuum, for example, a device of the general type disclosed in U. S. Patent No. 140,017, or preferably the Hydrovactor manufactured by The Allen-Sherman-Hoff Company of Philadelphia, Pennsylvania. This Hydrovactor is generally similar to the device of Patent No. 140,017, but specifically includes, as is shown in Fig. 2, a housing 11a having a Venturi-shaped axial passage 11b and an enlarged end portion 11c into which a high pressure water line 11d opens. The vacuum line 12 extends thru the enlargement 11c, as is indicated at 11e and water escapes at high velocity from housing 11c into the passage 11b thru a plurality of nozzles 11f which are disposed around extension 11e of line 12 and are inclined to project streams of water which converge just before reaching the smallest part of the passage 11b.

It will be evident from the foregoing description of Fig. 1 that the present invention includes several inter-related, but different, types of systems, viz: a vacuum system, a mechanical system, a hydraulic system and an electrical system. The vacuum system may be considered as comprising the dust valves 2, line 4, separator 5 and line 12. The mechanical system may be considered as comprising the device 6. The hydraulic system may be considered as comprising the circuits of Fig. 11 and the devices controlled thereby including the thrusters 3.

In Fig. 2 parts of the apparatus of Fig. 1 are shown in somewhat more detail. There two of the hoppers 1 are disposed beneath electrical precipitators 25 to receive dust precipitated from furnace gases traveling from the tube chambers of a powdered fuel burning furnace to the stack. The lower pair of hoppers 25a correspond to hoppers positioned to collect dust separating from the furnace gases in the tube chambers of such a furnace. Each of these hoppers is provided with a dust valve 2 which is shown in more detail in Fig. 3.

Each valve 2 comprises a housing 26 the interior of which is in communication with the interior of its hopper. At one end the valve has an air inlet pipe 27 in which is a check valve 27a to admit air but to prevent escape of dust, and at the other end has an air and dust outlet pipe 28 which connects the valve to pipe line 4. If desired, the inlet pipes 27 may be connected to the interior of the adjacent hoppers above the top of dust in the hoppers. In that event, gases from the hoppers would be drawn thru the valves instead of air. The outlet opening is controlled by a door fastened to shaft 29 which is rotatably mounted in housing 26 and which may be rotated by a lever 30 fastened thereto and engageable with a cam 31 keyed to a shaft 32. To insure the free movement of dust from hopper 1 into dust valve 2 a vibrator may be employed which, as is shown in Fig. 3, includes a plate 33 pivoted at its upper end within the hopper and attached at its lower end to a rod 34 which may be reciprocated by motor 35.

As is shown in Figs. 1 and 3, several hoppers 1 are served by a single thruster 3 thru the medium of shaft 32. Each thruster comprises a hydraulic cylinder and piston and a centrifugal pump for forcing liquid into the space within the cylinder and beneath the piston, thereby raising the piston by a rod 35a. This rod is pivoted to the arm 36 of a member 37 which is mounted to rotate on shaft 32 and which carries a pawl to

engage with ratchet 38 which is secured to shaft 32. When the rod 35a is forced upwardly the pawl engages the ratchet 38 and rotates shaft 32 thru a predetermined angular distance, and when the centrifugal pump is de-energized the piston moves downwardly in its cylinder under the influence of gravity, thereby pulling the rod 36 down and retracting the pawl to engage with the ratchet for the next operation of the thruster. It will be understood that several cams 31 on any shaft 32 are so disposed around the shaft that when one pawl engages its lever 30 to open the door of its valve the other pawls will not be in positions to open the doors of their valves; and that as one pawl 31 moves out of contact with its lever 30 so that the latter may move downwardly and its door may close, another cam 31 will be engaging its lever 30 to open the door of the associated valve.

The dust valves above described and other forms of valves which might be employed are shown and described and claimed in my copending application Ser. No. 464,720, filed November 6, 1942, as a continuation-in-part of application Ser. No. 429,269, filed February 2, 1942, now Patent 2,368,395, issued January 30, 1945. The thruster and its valve-actuating means are shown, described and claimed in my copending application Ser. No. 470,472, filed December 29, 1942, now Patent 2,368,396, issued January 30, 1945.

The dust valves 2 of Figs. 1 and 2 communicate thru lines 28 with line 4 as above described. This latter line leads into separator 5. While various types of separators may be employed, a satisfactory type is that shown in some detail in Figs. 4, 5 and 6.

Separator 5 consists of a receptacle having side walls 40, a bottom wall 41 provided with outlet openings 42 therethru, a bottom wall 43 which slopes downwardly toward each opening 42, an access door 44, a top cover 45, and an annular, inverted, U-shaped in cross-section member 46 adjacent to the inner side of the cover 45. Line 4 opens tangentially into the U-shaped interior of member 46, as is indicated at 47, and line 12 communicates with the interior of separator 5 thru opening 48 in the top central portion of the latter. It will be understood that when a condition of vacuum exists in line 12, separator 5 and line 4, and a dust valve is opened, air streams will flow thru the open valve thereby entraining dust in the valve and such air and entrained dust will flow thru line 28 and line 4 into separator 5. There it whirls around in member 46, passing out thru the lower open end thereof. The air will change direction and flow out thru opening 48 into line 12 while the dust will separate from the air more or less completely and will collect on the bottom walls 41 and 43 of separator 5.

Device 6 for transferring dust from separator 5 to storage hopper 7 is shown generally in Figs. 1 and 2 and in some detail in Figs. 4, 5 and 6. This transfer apparatus 6 is enclosed in a housing 50, a part of the upper wall of which is wall 41 of separator 5, the side walls of the housing being indicated at 51 and the bottom wall 52 having a circular opening to receive the open upper end of a conically shaped hopper 53 which communicates with the interior of storage hopper 7. Since the dust to be handled is extremely fine, it is important that all the joints of housing 50 should be tight enough to prevent passage of dust therethru. This housing 50 may be supported partly

by the legs 54 which support separator 5 and partly by other legs 55. As illustrated, the housing 50 is, in plan view, a rectangle with rounded ends. Within housing 50 and near the ends thereof are mounted two vertical shafts 56 each having keyed thereto a sprocket wheel 57. One of these shafts 56 is an idler shaft while the other one is driven. This driven shaft is attached to a pulley 58. A motor 59 working thru reduction gearing 60, pulley 61 and belt 62, which is trained around pulleys 58 and 61, serves to rotate the driven shaft 56 and its sprocket wheel 57. An endless chain 65 provided with transversely extending disc-shaped members 66 which may be called pistons, is trained around sprockets 57 and when one sprocket 57 is rotated this chain is driven and in turn drives the other sprocket. The direction of travel of chain 65 is indicated by the arrows in Figs. 4 and 6.

To minimize sagging of the chain 65 hollow cylinders 67 are disposed adjacent to each sprocket 57, as is best shown in Fig. 6. The bores of these cylinders 67 are slightly larger in diameter than the pistons 66, and cylinders 67 are so positioned within the housing 50 that the lower edges of pistons 66 will engage the lower inner surface of the cylinders when the chain is substantially horizontal or free from sagging.

Openings 42 communicate with the interior of two elongated cylinders 70. These cylinders are preferably provided with water jackets 71 into which cooling water may be led thru pipes 72 and from which water may be carried away thru pipes 73. These cylinders 70 surround the endless chain 65 and are aligned therewith so that the chain may pass axially therethru. The diameter of the bore of each cylinder 70 is substantially the same as the diameter of pistons 66 at operating temperatures. As a result of this relatively close fit between the peripheries of the pistons 66 and the inner surface of cylinder 70 little, if any, air can pass thru cylinder 70 from hopper 53, where atmospheric pressure may exist, to the interior of separator 5 where a vacuum amounting to as much as 5" of mercury, or even more, may exist. Furthermore, the pistons 66 serve to propel dust which passes thru openings 42 to the ends of the cylinders 70, where it falls into the upper end of hopper 53 between the adjacent ends of cylinders 67 and 70.

The pistons 66 may take several different forms. The preferred form, which is illustrated in Figs. 5 and 6, comprises a pair of mutilated metal discs 75 spaced a predetermined distance apart and smaller in diameter than the bores of cylinders 67 and 70, and a disc 76 which is preferably composed of rubber or flexible, substantially non-compressible, material. These discs 76 comprise a thin portion lying between mutilated discs 75 and extending therebeyond to engage the inner surface of cylinder 70, and a thickened sector-shaped portion substantially as thick as the combined thickness of discs 75 and the thin portion of 76. In other words, the plates 75 are discs which have been mutilated by removal of sector portions and the member 76 has been thickened to occupy the space provided by removal of those sector-shaped portions. The thickened portions of member 76 are disposed at the lower sides of piston 66 so that they will carry part of the weight of the chain by engaging the lower portion of the interior surface of cylinder 70 while the thinner portions of member 76, which do not have to bear such weight, need only seal the cylinder against passage of material amounts of

air thru the cylinder and also propel dust from opening 42 to the end of the cylinder.

It will be understood that when dust is being separated in separator 5 from the air which transferred it from hopper 1 to the separator, the transferring device 6 should be in operation. When operated and dust is present in separator 5 the dust slides down bottom wall 43 and feeds into openings 42 and thence into the interior of cylinders 70. The moving chain 65 propels pistons 66 thru cylinders 70 and moves the dust from openings 42 to the end of the cylinders, where it may fall into hopper 53. Even tho a considerable vacuum may exist in separator 5 and atmospheric pressure may exist in hoppers 53 and 7, no material amounts of air can pass thru cylinders 70 into separator 5. As a result, dust may be continuously withdrawn from one after another of a plurality of hoppers 2, continuously separated from the air in separator 5, and continuously transferred to hopper 7 without any material disturbance of the condition of vacuum being caused by the transference of the dust from the separator to hoppers of 53 and 7. In other words, a separator 5 of modest size can be used in this manner and yet many tons of dust may be removed from a plurality of hoppers without the necessity of breaking and again building up the condition of vacuum at short intervals of time.

Figures 7 to 10 inclusive show in greater detail a hydraulic apparatus which is indicated generally by reference numeral 8 on Figs. 1 and 2. As shown on these latter figures, device 8 is in communication with hopper 7 thru a conduit 80 which is provided with a slide valve 81 and a rotating valve 82 actuated by motor 83.

Device 8 comprises a stationary, tubular feeder 85, a rotatable tubular mixer 86 and a stationary discharge tube 89 which has an opening 90 in its lower portion to deliver material therefrom into a transporting device such as hopper car 9. Means 85 and 86 are axially aligned and are inclined downwardly by supporting frame-work 91.

Referring more particularly to Fig. 7, it will be seen that member 85 projects at its lower end into the upper end of member 86 and that these adjacent ends are sealed against escape of dust by a housing 100 within which is located a ring gear 101 attached to the upper end of member 86. This ring gear meshes with a pinion on motor 102. Member 86 is provided with exterior annular tracks 103 which rest and run on rollers 104. The lower end of members 86 extends into housing 89 and has a fairly dust-tight connection therewith, as indicated at 105.

A spider 110 is secured to member 86 near its upper end and is provided on the axis of member 86 with a tubular bearing 111 on one side thereof and with a driving socket 112 on the other side thereof. A screw conveyor 113 is disposed in member 86 with the outer edges of its spiral veins 114 lying fairly close to the inner surface of member 85. As shown, this conveyor has a stub shaft 115 at its upper end rotatably positioned in bearing 116 and at its lower end a stub driving shaft 117 which seats in driving socket 112. It will be understood that when member 86 is rotated driving socket 112 of spider 110 will rotate screw conveyor 113 and will move dust from the lower end of conduit 80 into the upper end of member 86.

A cylindrical member 120, which may be a length of pipe, has its upper end rotatably

mounted in bearing 111 of spider 110 and its lower end supported and held against rotation by housing 89. When member 86 rotates this cylinder 120 does not rotate.

Member 120 has secured to it within member 86 two axially spaced baffles 121. These baffles are substantially alike and are shown in side elevation in Figs. 8 and 9. Preferably, baffles 121 are slightly less in radial length than the radius of member 86 and have peripheries which are slightly less than 180° in extent. Each baffle 121 is preferably provided at its lower edge with an adjustable and replaceable shoe 122, for I have found that these baffles tend to wear away more quickly at that place than elsewhere.

The cylindrical member 120 also has secured thereto a plurality of scrapers 125 spaced therealong. These scrapers extend out close to the inner surface of member 86 and serve to prevent mixtures of dust and water from clinging to and rotating with the member 86.

A water line 130 extends in thru the end wall of housing 87 and is provided with a plurality of nozzles 131, 132 and 133. A branch pipe 134 is provided with nozzle 135. Pipe line 130 is attached to member 120.

It will be understood that when dust is delivered from hopper 7 thru conduit 80 and into member 85 and drum 86 is rotating the dust will be propelled thru member 85 by conveyor 113 and discharged into member 86. Water sprayed onto the dust from the nozzles of pipes 130 and 134 will moisten the dust and cause it to ball up as it moves toward the lower end of rotating member 86. This moist dust tends to fill the spaces between baffles 121 and the interior surface of member 86 and seal them against egress of dry dust while the scrapers 125 prevent the moistened dust from clinging to and rotating with the drum and scrape the moist masses from those walls and drop them onto the far side of the adjacent baffles 121. The water sprayed into member 86 is regulated in accordance with the amount of dust therein, so that the dust will be moistened and the particles will cling together much like moist earth, and such moist masses will be discharged from the lower end of member 86 where they can pass thru opening 90 into a conveyance. In that condition these masses are substantially free from dry dust which could be blown away.

In Fig. 11 are shown electrical circuits for actuating the thrusters 3 to open and close a plurality of valves 2 in sequence and in accordance with the degree of vacuum existing in the vacuum system.

Fig. 11 shows power lines 140 and 141 which may be connected to a suitable source of power thru switch 23 on panel 15. Several circuits, A, B, C and D, are associated with lines 140 and 141 and the first three of these circuits include banks of contacts E, F and G and rotatable switches or selectors H, I and J. These contacts and selectors constitute parts of a switching device which is made and sold by the General Electric Company and is known as an Automatic Supervisory Switchgear Multiposition Selector. The switches H, I and J are mounted on a rotatable shaft and move simultaneously when the shaft rotates.

In circuit A line 142 connects power line 141 with fixed terminal 143 of the selector while line 144 leads from power line 140 to switch 145 which is connected thru point 0 of the E bank of contacts with the movable switch H. Switch 145 is control switch 24 on panel 15. When switch 145 is closed current will flow thru the aforesaid cir-

cuit and energize the selector matching coils, the selector thereby shifting switches or selectors H, I and J from points 0 to 1 of each bank. Current will thereupon flow thru line 150 of circuit B, bank G and line 151 of circuit C thereby energizing contactor N1 of the latter circuit, this contactor in turn closing contact 152 of circuit D and energizing thruster 153. This thruster 153 is one of the thrusters 3 of Fig. 1. The thruster is actuated by actuation of its motor which drives the pump of the thruster. When actuated the thruster rotates shaft 32 of Fig. 3 to open the outlet door of a valve 2 thereby permitting the vacuum in the system to induce a flow of air thru the valve. If the vacuum in line 4 was above the predetermined amount when the dust valve was opened contact VU of a vacuum relay in line 146 closes and energizes relay T1 and contacts on T1 close and energize relay T2. Contacts on relay T2 close and energize the selector notching coils to step the selectors H, I and J to points 2 on banks E, F and G.

When the vacuum in the system falls below a predetermined value, contactor VD in line 147 closes and causes the selector notching coil to operate thru relays T1 and T2 and move the selector to points 3. This operation takes place when substantially all the dust has been removed from the first hopper.

When the selectors are on points 3, contactor N1 is again energized and thruster 153 is operated thereby rotating shaft 32 enough to move cam 31 out of contact with lever 30 thereby allowing the door of that valve to close, and moving another cam 31 against its lever 30 thereby opening the door of that valve. The vacuum increases in the system as soon as the door of the valve of the empty hopper is closed and when it reaches the predetermined amount relay VU closes. Then the operations which are described above after the closing of relay VU are repeated. These operations are repeated for each valve on the first thruster.

When the last hopper associated with the first thruster is emptied of dust the selectors have been stepped to point 9. Thereupon contactor N2 in line 154 is energized and the second thruster 153a is energized thru contact 152a and opens the first valve of the group of valves controlled thereby. At the same time contacts of G1 in line 160 of circuit B energize contactor N1 to close the last valve of the first group of valves.

This sequencing continues thru the third thruster, (or thru more than three thrusters provided the necessary additions are made to the circuits of Fig. 11) until the selector reaches the 0 point which is an open switch in the circuit to bank E. The switch 24 must be closed before the above described operations can be repeated.

The contacts, VU and VD, have connections associated with vacuum gage 14 of panel 15 (Fig. 1). Contact VD is closed by these connections while the vacuum gage 14 registers from zero to some predetermined extent of vacuum, for example, 5" of mercury, and contact VD is open while the vacuum is greater than that predetermined amount. Contact VU is open while the vacuum is below a predetermined value, for example, 8" of mercury but is closed while higher values exist in the system.

The operation of the above described apparatus is substantially as follows: Assuming that the various described parts have been installed and connected as shown and described, and that there is an accumulation of dust in a plurality of hop-

pers 1 which the operator desires to remove, the furnace operator opens valve 10a in main water line 10 thereby admitting water under pressure to the vacuum creating device 11. Then he opens valve 12a in vacuum line 12 thereby permitting the vacuum creating device to withdraw air from the vacuum system, including line 12, separator 5, and line 4. The operator then energizes motor 59 of the dust transferring device thereby setting in operation the endless conveyor 65. When the vacuum in the system has reached the predetermined minimum amount as recorded by gage 17 on panel 15 the operator closes main power switch 23 thereby energizing power lines 140 and 141 of Fig. 11. Then the operator shifts control switch 24 to the starting position thereby energizing the selector and shifting the contacts thereof in banks E, F and G to the point 1 position. Thereupon the thruster for the first group of dust valves 2 is actuated with the resultant opening of the door of the first valve of this group of dust valves 2. Air under the influence of the vacuum existing in the system flows thru the valve, entraining with it dust from the hopper and carrying that dust thru line 4 and into separator 5 where the dust and air are separated, the dust collecting in the bottom of the separator while the air escapes thru line 12. The dust which is separated in the separator flows thru openings 42 and is propelled by the pistons on conveyor 65 to the ends of the cylinders 70 and is there discharged into the upper end of hopper 53 and thence falls into storage hopper 7. When substantially all the dust has been removed from one hopper of the first group of hoppers and the vacuum decreases in the line, the selector automatically actuates the thruster of that group of valves thereby permitting the closing of the door of the just emptied hopper valve and opening the door of the next valve.

This sequence of operations is repeated for each of the valves of the group associated with the first thruster and continues thru the next group of valves associated with the second thruster and so on to the successive group of valves and their thrusters until substantially all the dust has been removed from all the hoppers, whereupon the selector arrives at an open switch and the electrical system ceases to function until re-energized by movement of the control lever 24 to the starting position.

During all this time the dust transferring device 6 has been transferring dust from separator 5 to storage hopper 7.

When the dust has all been removed from the several hoppers the operator closes valves 10a and 12a. Since it is desirable that there should be no flow of water in line 12, means are provided for drainage of water out of water line 16. While the water pressure is on this line water flows thru branch lines 18 and 19 and the pressure of water in line 18 actuates valve 20 to close the drain valve connected to branch line 19. When valve 10 is closed the pressure on water in line 16 falls by reason of the water in that line escaping thru device 11 and coincident with that fall in pressure the piston in valve 20 is restored to normal position, thereby opening the drain valve in line 19 and permitting water to escape therethru. As this water pressure decreases the spring in valve 21 opens that valve and permits air to flow therethru and into line 12. Thus water drains out of the system without backing up in line 12.

11

It will be understood that the dust in hopper 7 must be removed therefrom but may be removed only at fairly long intervals such as once a day or so because of the large capacity of hopper 7.

When dust is to be removed from hopper 7 the motor 102 is energized, thereby rotating conveyor 113 and drum 86. Water is admitted into lines 130 and 134 to discharge thru the several spray nozzles 131, 132, 133 and 135. The slide valve 80 is opened and rotary valve 82 is set in motion by energizing motor 83. Thereupon dust in hopper 7 passes thru conduit 80 and into member 85 where it is propelled by a conveyor 113 into drum 86. There it is mixed with the water from lines 130 and 134 and the moistened or wetted dust discharged from the lower end of drum 86 discharges into a conveyance such as car 9.

Since the dust discharged into hopper 7 displaces air therein, some venting means should be provided to permit such displaced air to escape. Since the dust discharged into hopper 7 is extremely fine and tends to be moved by currents of air, the venting means should be such as to permit escape of air while preventing the escape of dust with the air. Any suitable means may be employed for these purposes but, as is shown in Fig. 5, a simple means consists of a finely woven fabric cylinder 200 which is attached to the walls 201 defining an outlet opening from the hopper 7. This flexible cylinder 200 is enclosed in a housing 202 which has one or more outlet openings 203 on the top thereof. The upper end of member 200 is preferably attached to a member 204 which has an extension in the form of a rod or chain 205 extending thru the top of housing 200. This extension 205 may be held in a position to maintain member 200 extended but member 205 may be reciprocated thereby shaking member 200 and dislodging from the interior thereof any dust which may be adhering to it.

It will be seen from the foregoing description that the present invention provides a system, method and apparatus which will remove dust from a plurality of hoppers in succession by air moving thru a vacuum system, and that the dust entrained in the air is continuously separated therefrom and transferred to a chamber under atmospheric pressure without any interruption of the operation of the vacuum system; and that the dust in the latter hopper is so conditioned that it may be handled and disposed of without substantial quantities thereof being picked up by moving air currents. It will also be observed that the present invention provides a system, method and apparatus which are in part automatic and in part semi-automatic and which require the minimum amount of personal attention by an operator. It will further be seen that this invention makes it possible for one operator to remove periodically or substantially continuously, if desired, the dust produced by a large powdered fuel burning furnace and to handle many tons of such dust per day while preventing the dust from becoming a nuisance other than as regards the expense of the equipment and the small amount of labor cost for the operator. The cost of the apparatus is quickly offset by the savings in labor as compared with previous dust handling systems and apparatus.

Having thus described the invention so that others skilled in the art may be able to understand and practice the same, I state that what

12

I desire to secure by Letters Patent is defined in what is claimed.

What is claimed is:

1. A system for handling dust comprising a plurality of dust-collecting chambers, a dust and gas separating chamber, a vacuum creating device, a passage selectively connecting each dust collecting chamber with said separating chamber, and with said vacuum creating device, an electrical circuit, means automatically actuated by predetermined amounts of vacuum in said passage between said collecting chambers and said vacuum creating device to energize said electrical circuit, and control means actuated by said circuit when energized to shift said flow of gas from one dust-collecting chamber to another such chamber.
2. Apparatus for handling dust comprising a plurality of dust-collecting hoppers each having a dust discharge opening, a valve for each hopper for receiving dust discharged thru the said opening thereof and having a gas inlet opening and a dust and gas outlet opening, a separator for separating said dust and gas, piping connecting said valve outlet openings with said separator, means associated with each valve for controlling the flow of gas and dust thru its dust and gas opening, a vacuum creating device for creating a vacuum in said separator and piping and, when the said outlet opening of any valve is open, for causing a flow of gas thru such valve and piping into said separator, electrical means actuated by the vacuum existing in said pipe between said valves and said vacuum creating device and operable to actuate said valve control means to opened and to closed positions, and means for removing dust from said separator while a condition of vacuum exists in the separator.
3. A material handling system comprising in combination, a plurality of material containers, a common discharge conduit for said containers, means for producing subatmospheric pressures in said conduit, a separate valve for each of said containers for completing and interrupting connections from said containers to atmosphere and to said conduit, a selector switching device having a plurality of operating positions, means responsive to changes in atmospheric pressure in said conduit for successively actuating said selector switching device to said operating positions, and means responsive to operation of said switching device to said positions for successively opening and closing said valves.
4. A material handling control system comprising in combination, a plurality of material containers, a common discharge conduit for said containers, a separate valve for each of said containers for connecting said containers to said conduit and to atmosphere, means for producing subatmospheric pressures in said conduit, a selector switching device having a plurality of operating positions, a starting control device for setting said selector switching device in operation, operating means for said valves responsive to operation of said selector switching device to said operating positions for successively opening and closing said valves, and a device cooperating with said selector switching device and responsive to a subatmospheric pressure in said conduit for actuating said selector switch to one of said operating positions and responsive to atmospheric pressure in said conduit for actuating said selector switch to a succeeding position.
5. Apparatus for handling fine solids comprising a plurality of hoppers to collect such solids,

a plurality of valves, one for each hopper, through which such collected solids may flow from said hoppers, each of said valves including movable closures, a passage for solids flowing from said valves, closure control means operatively connected with said closures, and an automatically actuated electrical system, said system including a device sensitive to different amounts of vacuum in said passage for energizing the control means of said valves successively to open one of said valves after an open valve has closed.

6. Apparatus for handling fine solids comprising a plurality of hoppers to collect such solids, a plurality of valves, one for each hopper, through which such collected solids may flow from said hoppers, each said valve including a movable closure, closure control means operatively connected with said closures, an electrical system including switching means for successively energizing the control means of only one of said valves at a time, and an automatically actuated, vacuum sensitive device operatively connected with said system for successively energizing said switching means.

FRANK B. ALLEN.
